[57]**CLAIM**

The ornamental design for a combined hose container and lid therefor, as shown and described.

DESCRIPTION

FIG. 1 is an exploded perspective view of a combined hose container and lid therefor showing my new design; FIG. 2 is a bottom plan view of the hose container lid; FIG. 3 is a bottom plan view of the hose container; FIG. 4 is a top plan view of the lid; and, FIG. 5 is a top plan view of the hose container. The broken line showing of a hose is for illustrative purposes only and forms no part of the claimed design.

FIG. 2

FIG. 3

FIG. 4

FIG. 5
